UNITED STATES PATENT OFFICE.

BENEDICT F. VOGT, OF LOUISVILLE, KENTUCKY.

REFRIGERATOR.

Application filed September 4, 1924. Serial No. 735,799.

This invention relates to refrigerators and other like devices wherein cabinets are employed having sliding drawers.

It is quite common in certain devices, such as filing cabinets and the like, to provide sliding drawers which run on an extension track. In such filing cabinets no necessity exists for removing the tracks although it is very ordinary to provide for lifting the drawers of the tracks. In refrigerators, however, it is essential, for sanitary causes, that not only should one be able to remove the drawers themselves but the tracks on which these drawers run should also be removable so that the entire inside of the refrigerator can, from time to time, be thoroughly scalded out and cleansed. In the modern type of refrigerator provision for this purpose is frequently made by forming the interior of the food compartments as a unitary structure.

One important object of the present invention is to provide a form of refrigerator having extensible drawer supporting slides arranged in a novel manner having detachable positions within the refrigerator.

A second, important object of the present invention is to provide an improved form of extensible slides peculiarly adapted for use with refrigerators of this class although it is also capable of use in filing cabinets and other places wherever extensible slides may be employed.

A third important object of the invention is to provide an improved form of slides of the above character and a drawer or other receptacle having elements cooperating with the slides so that the drawer may be pulled fully out without danger of dropping.

With the above and other objects in view as will be hereinafter apparent, the invention consists in general of certain novel details of construction and combinations of parts hereinafter fully described, illustrated in the accompanying drawings and specifically claimed.

In the accompanying drawings like characters of reference indicate like parts in the several views, and:

Figure 1 is a perspective view of a refrigerator constructed in accordance with this invention, the main doors of the refrigerator being shown open and one of the drawers and its rack being removed and shown in front of the refrigerator, a second drawer being removed but not shown.

Figure 2 is a plan view of the rack with a portion of the refrigerator walls shown in connection therewith.

Figure 3 is an enlarged detail section taken on the line 3—3 of Figure 2 but showing only the forward part of said figure.

Figure 4 is a section on the line 4—4 of Figure 2.

Figure 5 is a section to an enlarged scale of one side of the rack and showing the same in perspective, the sections being also taken on said line 4—4.

Figure 6 is a perspective view showing the manner of supporting the rack at the front thereof.

Figure 7 is an enlarged section on the line 7—7 of Figure 2, the view showing the slides in their fully extended position.

Figure 8 is a view similar to Figure 7 but showing the slides in fully collapsed position.

Figure 9 is a section also taken on the line 7—7 but showing the rack removed with the extension slide in position for disconnection from the fixed slide, the extension slide being shown in dotted lines in disconnected position.

Figure 10 is a section on the line 10—10 of Figure 9.

Figure 11 is a section on the line 11—11 of Figure 8.

Figure 12 is a section on the line 12—12 of Figure 9.

Figure 13 is a section on the line 13—13 of Figure 7.

In the construction of this refrigerator various types may be employed but, as an example there has been shown what is known as a "front icer", that is to say a refrigerator where the ice is placed in the refrigerator from its front side. The device as shown comprises a casing 10 supported on suitable castors 11 and this casing is of the usual heat insulating construction not deemed necessary to be here shown or described in detail.

The case is divided into an ice compartment 12 below which is a food compartment 13 and at one side of the two compartments just mentioned is a second food compartment 14; thus being three compartments in the case, two on one side of the case and one on the other side. Each of these compartments is closed by a suitable door 15 having the usual refrigerator door latch 16 and keeper 17. So far the construction is that quite common in any refrigerator. In the

present case, however, a drawer 18 slides in and out of the compartment 13, the drawer having its forward end of proper size to close the opening to the compartment 13 5 when pushed in and also having a back end 19 of such size as to fill the opening to the compartment when the drawer is drawn fully out and to engage the slides or supports, which will presently be described at 10 the front. Similarly the compartment 14 is provided with drawers 18 arranged one above the other and these drawers, when all are pushed in completely close the entrance or opening of the compartment 14. Each 15 drawer in this compartment has a back 19 which closes, when the drawer is pulled fully out, that portion to the compartment 14 formerly occupied by the front of said drawer. These drawers slide on certain extension racks which will now be described in detail.

Each of the extension racks consists of what may be termed a fixed member and sliding or telescopic member. Each fixed 25 member comprises a rear transverse member 20 preferably in the form of an angle iron and having one leg vertical and provided adjacent each end with an opening 21, best seen in Figure 13. These openings receive 30 pins 22 which project from the back wall of a compartment in which the rack is located. Similarly, the front member of the fixed slide is of angle iron form as shown at 23 and has one leg vertical and provided adjacent each end with a slot 24 fitting on a headed pin 25 projecting inwardly from the front wall of the refrigerator adjacent the opening to the compartment. The remaining legs of the members 20 and 23 extend 35 toward each other and secured to these legs are the bottom flanges 26 of side channels which are provided with relative wide bottom flanges and relative narrow top flanges 27 extending from the front ends 40 rearwardly and terminating at about the middle of the channel. Each of the sliding racks has a rear angle iron portion 28, one leg of which is horizontal and extends toward the front while the other leg extends 45 vertically upwardly from the rear edge of the first leg. Also there is provided a front tie member 29 parallel to the member 28 and these are connected on each side by a channel having a relative wide bottom flange 50 30 and a relative narrow top flange 31 which extends forwardly from the rear and to a point about half-way the length of said channel. The flanges 31 and 30 are spaced vertically so as to lie between the flanges 55 27 and 26 and each flange 30 has its edge portion elevated so that the end of the tie bar 29 may be received beneath the channel without lifting the front end of the telescopic slide. For purpose of strengthening 60 and stiffening the tie bar 29 a suitable rib

32 is stamped therein. On the front end of the web of each telescopic channel is fixed a lug 33.

Now it will be seen that so long as the telescopic channel is not moved back to such 70 position as to clear the flanges 27 it will be guided between these flanges and the flanges 26 and cannot tilt. It is to be noted that the vertical leg of the angle 28 is sufficiently high that it engages, when the telescopic 75 slide is drawn fully forward, with the inner ends of the flanges 27. Each drawer has on each side at its lower rear corners a projecting lug 34 which engages between the flanges 31 and 30 and each drawer also has a similar lug 35 carried about the middle of its lower edge, the spacing of the lugs 34 and 35 being such that when the drawer is drawn out the lugs 35 will engage the lugs 33 before the lugs 34 clear the front ends of the flanges 31. When the drawer is pushed 80 fully into the slides and in the position shown in Figure 8, the back of the drawer is against the vertical leg of the angle iron 28. As the drawer is pulled out the lugs 35 engage the lugs 33 and then the telescopic slide also moves out. This movement continues until the angle 28 engages the inner 85 ends of the flanges 27 in which position the part at the rear end 19 of the drawer will close the opening left by the drawer front. If it be desired to remove the drawer it is pulled out fully in this manner until the lugs 35 engage the lugs 33. The drawer may then be raised until the lugs 35 clear the lugs 33 and the drawer may then be pulled further forward until the lugs 34 clear the front end of the channels 31 whereupon the drawer may be fully lifted out. To move the slides the front end of the same is lifted up 90 to free the member 23 from the pins 25 and then the slides may be pulled forward so that the openings 21 move off of the pins 22. Then by twisting the slide at an angle it may be withdrawn from the compartment. 95 To separate the two members of the slide after the same is withdrawn it is merely necessary to pull the telescopic slide sufficiently far to the rear of the fixed slide for the side channels of the telescopic channels to close 100 the rear ends of the flanges 27.

There has thus been provided a simple and efficient device of the kind described and for the purpose specified.

It is obvious that minor changes may be 120 made in the form and construction of the invention without departing from the material spirit thereof. It is not, therefore, desired to confine the invention to the exact form herein shown and described, but it is 125 desired to include all such as properly come within the scope claimed.

Having thus described the invention, what is claimed as new, is:

1. The combination with a cabinet having 130

a compartment provided with an opening in its front, a drawer supporting telescopic rack including a pair of members connected by a depending front transverse bar and detachably supported on the front and rear walls of said compartment, and a drawer slidably and removably mounted on said rack and having a front wall provided with a depending lower edge engaging the transverse bar upon the drawer being moved to closed position.

5 2. The combination with a cabinet having a compartment provided with an opening in its front, a telescopic rack including a pair of members connected by a depending front transverse bar and detachably supported on

the front and rear walls of said compartment, a drawer slidably and removably mounted on said rack and having a front wall provided with a depending lower edge 20 engaging the transverse bar upon the drawer being moved to closed position, a second similar rack above said drawer for supporting a second drawer, the first mentioned drawer having the upper edge portion of 25 its front wall engaging the transverse bar of the second rack when closed and also having its rear wall projecting upwardly upon being moved to fully open position to also engage the said transverse bar of the said 30 second rack.

BENEDICT F. VOGT.
